DESIGN FOR A SPARK PLUG TESTER

Henry L. Hoke and Raymond W. Allen,
Akron, Ohio

Application February 10, 1940, Serial No. 90,186

Term of patent 14 years

To all whom it may concern:

Be it known that we, Henry L. Hoke and Raymond W. Allen, citizens of the United States, residing at Akron, in the county of Summit and State of Ohio, have invented a new, original, and ornamental Design for a Spark Plug Tester, of which the following is a specification, reference being had to the accompanying drawing, forming part thereof, in which:

Figure 1 is a top plan view of a spark plug tester showing our new design;

Figure 2 is a side elevation of the spark plug tester shown in Figure 1; and

Figures 3 and 4 are front and rear elevations of the spark plug tester shown in Figure 1.

We claim:

The ornamental design for a spark plug tester, as shown.

HENRY L. HOKE.
